UNITED STATES PATENT OFFICE.

JOHN V. W. VANDENBURGH, OF CHICAGO, ILLINOIS.

DESIGN FOR A BUTTON.

SPECIFICATION forming part of Design No. 21,151, dated November 3, 1891.

Application filed October 10, 1891. Serial No. 408,364. Term of patent 3½ years.

To all whom it may concern:

Be it known that I, JOHN V. W. VANDENBURGH, a citizen of the United States, residing at Chicago, in the county of Cook and State 5 of Illinois, have invented and produced a new and original Design for Buttons, of which the following is a specification, reference being had to the accompanying drawings, forming a part thereof, in which—

10 Figure 1 is a perspective view of the button. Fig. 2 is a face elevation of the button.

My design is specially intended in its present application as a button to be worn with cuffs or on the lapel of a coat or other place 15 of display for its leading and essential feature, hereinafter set forth and illustrated in the drawings, to present when viewed in elevation the representation of an egg struck and flattened on its under face and on its 20 apex or small end.

In the drawings, A represents the raised oval-shaped face of the design having the base-line for its sides and one end curved, and having the apex end cut by a face in cross plane, with lines running therefrom over 25 the apex end of the face A, producing, when viewed in front elevation, the outline of an egg having a flat and crushed apex end.

B is a stud for the attachment of a fastening, by means of which the button can be secured in the place where worn or displayed. 30

The essential feature of the design is a button having the representation in outline of an egg, with its apex end crushed and having the lower face thereof flattened. 35

What I claim as new, and desire to secure by Letters Patent, is—

The design for a button, substantially as herein shown and set forth.

JOHN V. W. VANDENBURGH.
